UNITED STATES PATENT OFFICE.

ERNEST SCOTT, OF PROVIDENCE, RHODE ISLAND.

DESIGN FOR A REPAIRING-PATCH FOR BICYCLE-TIRES.

SPECIFICATION forming part of Design No. 27,149, dated June 1, 1897.

Application filed April 17, 1897. Serial No. 632,673. Term of patent 14 years.

To all whom it may concern:

Be it known that I, ERNEST SCOTT, a citizen of the United States, residing at Providence, in the State of Rhode Island, have invented and produced a new and original Design for a Repairing-Patch for Bicycle-Tires, of which the following is a specification, reference being had to the accompanying drawings, forming a part thereof.

10 In the accompanying drawings, Figure 1 represents a side view, Fig. 2 an end view, and Fig. 3 an axial section, of a repairing-patch embodying my design.

The leading feature of my design consists 15 in a conical flange the apex of which is provided with a dome-shaped head and having a shank of cylindrical or of slightly-enlarging form extending concentrically from the base of the flange and having an aperture extend-

ing centrally through the shank and the flange and into the dome-shaped head.

In the drawings, *a* is the flange, having a flat annular base *b* and the conical surface *c*, having at its apex the dome-shaped head *d*. The shank *e* extends concentrically from the base *b* of the flange and is made in a cylindrical or slightly-expanding form, as shown in Fig. 3 by the full and dotted lines, and an aperture *f* extends centrally through the shank *e* and flange *a* into the dome-shaped head *d*.

What I claim is—

The design for a repairing-patch for bicycle-tires, herein shown and described.

ERNEST SCOTT.
